US0D1074468S

(12) **United States Design Patent** (10) **Patent No.:** **US D1,074,468 S**
(45) **Date of Patent:** **** May 13, 2025**

(54) **INFRARED THERMOMETER**

(71) Applicant: **ScopeAround**, Irvine, CA (US)
(72) Inventor: **Yingjie Sun**, Irvine, CA (US)
(73) Assignee: **SCOPEAROUND**, Irvine, CA (US)
(**) Term: **15 Years**
(21) Appl. No.: **29/915,314**
(22) Filed: **Oct. 27, 2023**
(51) **LOC (15) Cl.** **10-04**
(52) **U.S. Cl.**

(57) **CLAIM**

The ornamental design for an infrared thermometer, as shown and described.

DESCRIPTION

FIG. 1 is a front, top perspective view of an infrared thermometer, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the infrared thermometer that form no part of the claimed design.

1 Claim, 8 Drawing Sheets
